UNITED STATES PATENT OFFICE.

HARLAN S. NOYES, OF BROOKLYN, NEW YORK.

DESIGN FOR A WATCH-CASE OR LOCKET.

SPECIFICATION forming part of Design No. 18,533, dated August 14, 1888.

Application filed May 18, 1888. Serial No. 274,330. Term of patent 14 years.

To all whom it may concern:

Be it known that I, HARLAN S. NOYES, a citizen of the United States, residing at Brooklyn, in the State of New York, have invented and produced a new and original Design for 5 Watch Cases or Lockets, of which the following is a specification, reference being had to the accompanying drawing, forming part thereof.

10 The drawing is a front or face view of a case, in which A is the back or lid, and B the rim or center, of the case. This is made in the shape of a keystone, as shown, and extends beyond the exterior of the back or lid. The stem is 15 usually attached at the center of the rounded part, although it may be omitted or attached

elsewhere at will, as it forms no part of my design.

The leading features of this my design consist of the circular part A and the part B in 20 the form of a keystone.

What I claim as new, and desire to secure by Letters Patent, is—

The design for a watch-case or locket herein shown and described, consisting of a case the 25 outline whereof is in the form of a keystone, substantially as specified.

HARLAN S. NOYES.
